CLAIM

We claim, the ornamental design for a display screen or portion thereof with animated graphical user interface, as shown and described.

DESCRIPTION

FIG. 1 is a first image in a sequence for a display screen or portion thereof with animated graphical user interface showing our new design;

FIG. 2 is a second image in a sequence thereof;

FIG. 3 is a third image in a sequence thereof;

FIG. 4 is a fourth image in a sequence thereof; and,

FIG. 5 is a fifth image in a sequence thereof.

The broken line represents the display screen or portion thereof and form no part of the claimed design. The process or period in which one image transitions to another forms no part of the claimed design.
